CHILD'S ROCKING SEAT

Cecil Arthur Rassier, Erith, England

Application August 7, 1956, Serial No. 42,542

Term of patent 14 years

(Cl. D34—15)

FIG.1.

FIG.2.

FIG.3.

Fig. 1 is a front top perspective view of a child's rocking seat, showing my new design;

Fig. 2 is a rear bottom perspective view, showing the opposite side; and

Fig. 3 is a top plan view thereof.

I claim:

The ornamental design for a child's rocking seat, as shown.
